PORTRABLE LOADING VESTIBULE

Ronald C. Hinman, Mission Viejo, Calif., assignor to
Western Gear Corporation, Lynwood, Calif.

Filed Sept. 30, 1970, Ser. No. 25,292

Term of patent 14 years

Int. Cl. D25—99

U.S. Cl. D13—1

FIG. 1 is a front perspective view of a portable loading vestibule in a down position showing my new design;

FIG. 2 is a rear perspective view of the design of FIG. 1 in a down position;

FIG. 3 is a front perspective view of the design in an elevated position showing an escape ladder in an extended position and the stabilizing outriggers in extended position; and

FIG. 4 is a rear perspective view of the design illustrated in FIG. 3.

I claim:

The ornamental design for a portable loading vestibule, substantially as shown and described.
